UNITED STATES PATENT OFFICE.

JAMES D. REEKIE, OF ST. PAUL, MINNESOTA.

GASOLINE GAUGE.

Application filed April 10, 1926. Serial No. 101,089.

My invention relates to a gasoline gauge particularly applicable for use in the type of automobiles in which the fuel tank is located forward of the driver's seat and above the engine. In such autos the tank is usually arranged transversely under the cowl and forward of the so-called instrument board. The object of this invention is to provide a simple, accurate and inexpensive device readily installed in cars of the class mentioned and by which the driver or any other occupant of the car can readily see at any time what amount of fuel is in the tank.

In the accompanying drawing:

Fig. 1 is a longitudinal sectional elevation of the instrument board, cowl and fuel tank in approximately their relative positions and my improved gauge in operative position.

Fig. 2 is an enlarged top view about as on line 2—2 in Fig. 1.

Fig. 3 is an approximately full size sectional view as on line 3—3 in Fig. 2 showing the pivot mounting of the float lever of my device.

Fig. 4 is a face view of the gauge disc of my device about as on line 4—4 in Fig. 2.

Referring to the drawing by reference numerals, 5 designates the so-called instrument board of an automobile; 6 is the cowl normally extending forwardly and downwardly toward the engine hood (not shown); 7 is the fuel intake opening in the cowl and 8 the usual hinged cover for said opening. 9 is the usual fuel tank which is arranged transversely under the cowl and forward of the instrument board 5 about as shown and having a fuel intake 10 under the opening 7.

My device comprises an indicator disc 11 of arcuate form, or segmental, and having a vertically flanged edge 11^a. Said disc is pivoted as at 13 to the forward end of the horizontal arm 12^a of an inverted L-shaped bracket the vertical arm 12^b of which is suitably secured as at 14 to the front side of board 5 (see Figs. 1 and 2). The flange 11^a of the disc is normally directed rearwardly and oscillation of the disc causes its flanged part to pass an aperture 15 of the instrument board. At one side of the fulcrum 13 of disc 11 I provide a number of apertures arranged on a segment concentric to 13 and in either one of which may be suitably engaged the rear end of a reach rod 16 the front end of which is pivotally connected with the upper end of one arm 17^a of a

tilting lever 17—17^a. Said lever 17—17^a is fulcrumed on a transverse pin 19 extending across a slot 18^a in a flanged bushing 18 projecting upwardly through an aperture 20 in the tank. 21 is a nut engaging the upper exposed end of the bushing 18. The lever 17 is preferably of flat bar material as shown and at its fulcrum is formed with a circular enlargement 17^b of a size to fit snugly in the slot but prevent splashing fuel from passing upwardly through the slot. 17^a is a short vertical arm above the fulcrum 19 and 17 is a long arm directed downwardly and forwardly within the tank and carrying a suitable floating element 22 at its free end. Gasoline 23 in the tank causes float 22 to rise when the tank is being filled and descend as the gasoline is being used up. This of course rocks the lever 17—17^a of which 17^a automatically moves the reach rod 16 which in turn rotates disc 11. The flange 11 has a graduated scale of numbers on its outer face and which are visible through slot 15 thus at all times indicating the quantity of gasoline in the tank.

The use of my device and its construction have been fully disclosed. It is obvious that when the gasoline tank is being filled the float 22 will rise causing lever arm 17^a to push rod 16 rearwardly and the disc 11 is rotated in direction of arrow 25 (Fig. 3) exposing the numbers on flange 11^a at opening 15 according to the number of gallons or other units of gasoline in the tank. As the gasoline supply diminishes during the use of the car the float 22 goes down, pulling the reach rod 16 forwardly and the numbers on the flange 11^a are exposed accordingly.

26 is a pivot member for holding the forward end of the reach rod 16. It is threaded centrally, horizontally and also drilled transversely of its threaded part and through the threaded part for slidably receiving reach rod 16. 27 is a machine screw or other suitable headed screw passed through an aperture in the upper end of arm 17^a thence screwed into the threaded part of member 26 until it engages and holds rod 16.

What I claim is:

1. A fuel gauge for automobiles having a fuel tank in proximity to a fixed vertical element, having an aperture therein, said fuel gauge comprising a float within the fuel tank, a lever oscillatable in a vertical plane

and mainly within the tank, said float fixed on said lever, means for fulcruming said lever at the top part of the fuel tank, said lever having an arm extending upwardly outside of the fuel tank, a reach rod pivotally secured with one end to the upper end of said upper lever arm and extending toward the said fixed element, a segmental horizontally oscillatable gauge member mounted pivotally adjacent said fixed element, a vertical rim on said gauge member with graduated numerals thereon adapted to be exposed consecutively to view in said aperture in the fixed element, said float adapted to oscillate the lever in a vertical plane to actuate the rod and the gauge member in approximately horizontal plane.

2. The structure specified in claim 1, in which said fulcrum means of the vertically oscillatable lever comprises a horizontal pin, a flanged bushing removably securable in

the upper part of the fuel tank, said bushing having a vertical slot and said horizontal pin fixed in the bushing across said slot, an enlargement of said lever concentric of its fulcrum and adapted to close said slot but permit oscillation of the float-lever.

3. The structure specified in claim 1 in which said adjustable means connecting the reach rod and the lever comprises a horizontally disposed pivot member threaded centrally and drilled transversely through said threaded part for slidably receiving the reach rod, there being an aperture provided in the upper lever arm, a headed screw passed through said aperture and adapted to be screwed into the threaded part of the pivot member and frictionally engage the reach rod.

In testimony whereof I affix my signature.

JAMES D. REEKIE.
